UNITED STATES PATENT OFFICE.

CLAUDE MARIUS DREVET, OF PARIS, FRANCE.

ROTARY PUMP.

Application filed February 12, 1923. Serial No. 618,698.

This invention relates to improvements in machines driven by a liquid or gaseous fluid and also to improvements in machines serving to draw and force such fluid, and its object is to provide an improved machine of this kind arranged for use either as a fluid driven or as a fluid pumping machine and which is simple in construction, may be readily manufactured, and is reliable in operation.

One form of the invention is illustrated in the accompanying drawings, in which—

Fig. 1 is a sectional view on the plane indicated by the line D—E of Fig. 2.

Fig. 2 is a sectional view on the plane indicated by the lines A—B of Fig. 1.

If considering the drawings from the point of view of a motor, it will be noticed that the pressure of a gas, of a liquid, or the expansion due to the explosion of a carburetted gas applied at V, will effect a rotary motion of the whole movable system, the exhaust being rendered possible through O' in the direction of the arrow. Therefore, the system implies the idea of a motion exerting pressure, and of the exhaust or escape of the latter at each rotation.

Considering the same drawings from the point of view of drawing and forcing machines, supposing the rotation going on in the direction of the arrow, the drawing or sucking will take place at O between the point of the tangent and the pallet in the engendered volume V, while on the other side in the volume V' which is constantly diminishing, compression or forcing will result. Hence such case implies the idea of aspiration and of forcing.

Referring especially to Fig. 1, this figure shows an outer shell j in the interior of which is a cylinder e led in its rotary motion by a pallet i articulated at one of its extremities in the outer shell j and sliding with the aid of rollers with ball bearings in the interior of the cylinder e.

The outer shell j, to the lateral faces whereof the heads g, g' are fastened, revolves around a central, fixed axis, while the central cylinder rotates around an axis which is also fixed but displaced eccentrically with regard to the said central axis.

a indicates a central shaft fixed to a suitable structure and kept immovable. The inner cylinder e is eccentrically arranged in

the outer shell j and the shaft a being fixed, the crescent formed by the eccentricity of the cylinder e in the shell j does not change its configuration. The tangential point remains constantly situated in the prolongation of the axis A C passing through the two centers of rotation of the big shell j and of the inner cylinder e.

The shell j has ducts at one side at the center and also has a peripheral port O'. The cylinder e has a peripheral port O. A radially arranged pallet i is slidable through the periphery of the inner cylinder, lies in a plane extending through the center of said inner cylinder, is of such length as to extend through the center of the inner cylinder and has its outer end pivotally mounted in the periphery of the shell j, as shown.

b is the centering ball bearing for the shell j. c is a fixed projection carrying at its extremity the oscillating bearing d, since it is mechanically advisable to prevent the inner cylinder from being influenced, owing to a lack of parallelism between the axis of rotation of the shell and the axis of the projection c. f and f' are segments assuring contact on the faces and hence the tightness of the inner cylinder against the faces. l and n are adjusted bars or the like assuring tightness of the pallet against the faces, and during its sliding motion in the interior of the core, light springs such as k assure contacts against the faces. h is the motion causing or the motion transmitting shaft placed in the same axis as the shaft a.

What I claim is:

In a rotary pump, a cylinder mounted for rotation and having ducts at one side at the center and a peripheral port; a smaller cylinder eccentrically arranged in the first-named cylinder, having a fixed axis of rotation and further provided with a peripheral port, said cylinders being in mutual peripheral contact at one point, and a radially arranged pallet, lying in a plane extending through the center of the inner cylinder, slidable through the periphery of said inner cylinder, of such length as to extend also through the center of the inner cylinder and at its outer end pivotally mounted in the periphery of the first named cylinder.

In witness whereof I affix my signature.

CLAUDE MARIUS DREVET.
